(57) CLAIM

The ornamental design for fold-out cabinet bed with desk, as shown and described.

DESCRIPTION

FIG. 1 is a top perspective view of the design in a closed position with the desk supports attached and the desk in a raised position.

FIG. 2 is a top perspective view of the design in the closed position with the desk supports removed and the desk in a lowered position.

FIG. 3 is a top view of FIG. 1.

FIG. 4 is a bottom view of FIG. 1.

FIG. 5 is a front view of FIG. 1.

FIG. 6 is a back view of FIG. 1.

FIG. 7 is a left side view of FIG. 1.

FIG. 8 is a right side view of FIG. 1.

FIG. 9 is a top perspective view of the design in a partially open position with the desk supports removed and side doors closed.

FIG. 10 is a top perspective view of the design in a fully open position with the desk supports removed and the side doors closed.

FIG. 11 is a top view of FIG. 10.

FIG. 12 is a bottom view of FIG. 10.

FIG. 13 is a front view of FIG. 10.

FIG. 14 is a back view of FIG. 10.

FIG. 15 is a left side view of FIG. 10.

FIG. 16 is a right side view of FIG. 10.

FIG. 17 is a top perspective view of the design in a fully open position with the desk supports removed and the side doors opened.

FIG. 18 is a top view of FIG. 17.

FIG. 19 is a bottom view of FIG. 17.

FIG. 20 is a front view of FIG. 17.

FIG. 21 is a back view of FIG. 17.

FIG. 22 is a left side view of FIG. 17; and,

FIG. 23 is a right side view of FIG. 17.

The uniform broken lines showing in FIGS. 1-23 are for the purpose of illustrating portions of the fold-out cabinet bed with desk and form no part of the claimed design.

The dash-dot lines shown in FIG. 2 are for the purpose of illustrating removal of the desk supports from the cabinet bed and form no part of the claimed design.

The arrows shown in FIG. 17 are for the purpose of illustrating opening of the side doors and form no part of the claimed design.

1 Claim, 23 Drawing Sheets
